UNITED STATES PATENT OFFICE.

FRANK MESKER, CLARENCE E. SMITH, AND JACOB BEUC, OF ST. LOUIS, MISSOURI,
ASSIGNORS TO MESKER BROTHERS IRON COMPANY, OF ST. LOUIS, MISSOURI, A
CORPORATION OF MISSOURI.

METAL WINDOW CONSTRUCTION.

Application filed May 13, 1920. Serial No. 381,044.

To all whom it may concern:

Be it known that we, FRANK MESKER, CLARENCE E. SMITH, and JACOB BEUC, citizens of the United States, residing at St. Louis, Missouri, have invented a certain new and useful Improvement in Metal Window Constructions, of which the following is a full, clear, and exact description, such as will enable others skilled in the art to which it appertains to make and use the same, reference being had to the accompanying drawings, forming part of this specification.

Our invention relates generally to metallic window construction and more particularly to that type of metallic window having a stationary sash or frame and a swinging sash or frame which performs the functions of a ventilator, the principal objects of our invention being to provide a relatively simple, strong, durable, and economical construction that is capable of being easily and cheaply produced and which, when properly closed, is absolutely weather and dust proof.

Further objects of our invention are, to provide relatively simple and efficient means for mounting the swinging ventilator section upon certain of the rails of the window sash and which mounting permits the ventilator to be readily inserted or removed from the sash, and, further, to provide improved means for producing weather and dust tight joints between the ventilator section and the frame of the sash.

With the foregoing and other objects in view, our invention consists in certain novel features of construction and arrangement of parts, hereinafter more fully described and claimed, and illustrated in the accompanying drawings, in which—

Figure 1 is an elevational view of a metal window constructed in accordance with our invention and locking against the outer side or face thereof.

Figure 2 is a vertical section taken approximately on the line 2—2 of Figure 1.

Figure 3 is a perspective view of a short portion of one of the vertical side rails of the swinging ventilator frame and showing the arrangement of the flanges thereon.

Figure 4 is a perspective view of a short section of one of the upright members of the sash and showing an angle bracket po-

sitioned thereupon and which forms a support and bearing for the ventilator frame. 55

Figure 5 is an enlarged elevational view of parts of the upright side rails of the sash and ventilator frames and showing the means utilized for mounting the ventilator frame upon the sash. 60

Figure 6 is a horizontal section taken approximately on the line 6—6 of Figure 5.

Figure 7 is a horizontal section taken approximately on the line 7—7 or Figure 5.

Figure 8 is an elevational view of a portion of one of the upright rails of the sash and showing the swinging ventilator supporting bracket thereupon. 65

Figure 9 is an elevational view of one of the upright side rails of the ventilator frame. 70

Referring by numerals to the accompanying drawings which illustrate a practical embodiment of our invention, 1, 1 designate the upright side rails of the sash, 2 the top rail, 3 the bottom rail, 4 the mullions or intermediate upright rails, and 5 the intermediate transverse or horizontally disposed rails. All of these rails are preferably constructed of ordinary commercially rolled bars which are substantially T-shape in cross section and with the body portion of each rail or that portion including the laterally projecting flanges being substantially triangular in shape. 75 80 85

The rails making up the sash are rigidly connected to each other in any suitable manner, for instance, by being welded, brazed, or by having interengaging portions forced together by pressure. 90

The substantially triangular body portions 6 which include the lateral flanges 7 of the rails 1, 2, 3, 4 and 5 are disposed on the outer face of the sash while the webs 8 are disposed on the inner face of the sash. 95 The flanges 7 serve as supports for the panes of glass used in the window, said panes being secured to said flanges in any suitable manner, preferably with putty or cement. 100

One or more of the mullions 4 and transverse rails 5 are removed from the central portion of the sash to form a ventilator opening, and to provide bearings for the ventilator that occupies this opening, brackets 9 constructed from short sections of 105

angle bars are secured in any suitable manner to the inner faces of the webs 8 of the mullions 4 that are disposed immediately to the sides of said ventilator opening. Each 5 of these brackets has one leg or flange 9^a secured directly to the web portion 8 of one of the mullions and the other leg or flange 9^b projects inwardly from the web of the mullion that is toward the vertical section 10 of the ventilator opening. (See Figs. 4 and 8.)

The upper edges 10 of the inwardly projecting legs 9^b of these brackets constitute 15 bearings upon which the ventilator frame rocks during its swinging movements.

The ventilator frame comprises a pair of upright side rails 11, a top rail 12, bottom rail 13, one or more upright intermediate rails or mullions 14, and one or more intermediate transverse rails 15. The rails 12, 13, 20 14, and 15 are preferably formed from commercially rolled bars that are substantially T-shape in cross section while the upright side rails 11 are constructed from rolled 25 metal bars that are substantially channel-shape in cross section with certain of their lateral flanges cut away or mutilated. The T-shaped upright side rails of the ventilator frame are cut away so that certain of the 30 flanges on the upper part of the inside and on the lower part of the outside remain. These remaining flanges of the mutilated rails when the ventilator frame is in a vertical position, act as sealing members and 35 prevent the movement of said ventilator frame laterally and vertically, but allow it to be swung open to an angle of ninety degrees (90°) where horizontal and lateral movement is prevented by the engagement between 40 the mutilated flanges. (See Fig. 8.) When the frame is in a position approximately half-way between these extreme and locked positions, the ventilator frame may be removed from the sash by raising it out of engagement with the fulcrum flanges of the 45 fixed frame. Each upright side rail 11 comprises a web or body portion 16, and formed integral with the outer edge of the lower portion thereof is an outwardly presented flange 50 17 which, when the ventilator is closed, lies immediately against the outer edges of the lower portions of the mullions that are disposed immediately to the sides of the ventilator opening.

55 Formed integral with the inner edges of the upper portions of the webs 16 are outwardly presented flanges 18 which, when the ventilator is closed, lie immediately against the edges of the upper portions of the mullions that are disposed immediately to the sides of the ventilator opening. (See Figs. 6 and 7.)

When the ventilator frame is properly positioned in the sash, the lower edges 18^a 60 of the flanges 18 rest directly upon the

upper edges 10 of the inwardly presented flanges of the brackets 9, and thus the ventilator frame has broad and substantial bearings during its swinging movements.

Formed integral with and projecting outwardly from the web 16 of each upright rail 11 and arranged intermediate of its edges is a vertically disposed rib or flange 19, the lower end of which terminates in a plane shortly below the lower end of flange 18 and 75 when the ventilator is closed, the inner face of this flange lies immediately adjacent to the outer face of the corresponding flange 7 on the adjacent mullion. (See Fig. 6.)

Formed integral with the inner face of the 80 web 16 of each side rail 11 is an inwardly presented flange 20 which performs the functions of a pane supporting flange, said pane being held in place by putty or the like, as illustrated in Figures 6 and 7.

85 The rails forming the ventilator frame are secured to each other in any suitable manner, either by brazing, welding or by having interengaging parts upset by pressure to such a degree as to provide a firm and substantial connection. During the swinging movement of the ventilator, the lower edges of the flanges 18 bear directly upon the upper edges 10 of the brackets 9, thereby enabling said 90 ventilator to rock or swing freely from one 95 position to another and when closed, the flanges 17, 18 and 19 on the upright side members of the ventilator frame cooperate with the inner and outer edges and the inwardly presented flanges 7 of the adjacent 100 mullions to form weather and dust tight joints between the ventilator frame and sash.

105 Our improved ventilating sash is comparatively simple, strong and durable, is capable of being easily and economically produced, is constructed wholly of commercially rolled shapes which are readily obtainable in the open market, and the only rivets or like fastening devices utilized in the complete construction are those required for securing the angle brackets 9 to the mullions of the sash, and which brackets serve as 110 bearing for the swinging ventilator.

115 Obviously minor changes in the details of construction may be made by those skilled in the art, without departing from the spirit of our invention, the scope of which is set forth in the appended claims.

We claim as our invention:

120 1. In a metallic window construction, a metal sash, a ventilator opening therein, an inwardly extending flange on the inner face of said sash, terminating in an upwardly facing edge intermediate the top and bottom of the ventilator opening, a ventilator frame, an outwardly extending flange on the inner 125 face of said frame, terminating in a downwardly facing edge which is normally in substantial alignment with and resting upon the edge of said sash flange, said flanges 130

thereby cooperating as hinged members for swinging said frame in said sash.

2. In a metallic window construction, a metal sash, a ventilator opening therein, inwardly extending flanges on the inner faces 5 of said sash, terminating in upwardly facing edges intermediate the top and bottom of the ventilator opening, a ventilator frame, the sides of which comprise channel sections 10 having their flanges turned outwardly and engaging the inner and outer faces respec-

tively of the sash, the inner flanges terminating in downwardly facing edges supported on the upwardly facing edges of said sash flanges and pivoted thereon for swinging 15 said frame in said sash.

In testimony whereof we hereunto affix our signatures this seventh day of May, 1920.

FRANK MESKER.
CLARENCE E. SMITH.
JACOB BEUC.
